UNITED STATES PATENT OFFICE.

CHARLES SCUDDER, OF ALAMEDA, CALIFORNIA.

BOX, LOCK, AND HANDLE.

1,232,102.

Specification of Letters Patent.

Patented July 3, 1917.

Application filed August 5, 1914. Serial No. 855,342.

To all whom it may concern:

Be it known that I, CHARLES SCUDDER, a citizen of the United States, residing at Alameda, in the county of Alameda, State of California, have invented a new and useful Box, Lock, and Handle, of which the following is a specification in such full and clear terms as will enable those skilled in the art to construct and use the same.

10 This invention relates to a box, lock and handle for use with telescoping folding boxes and its object is to secure the two parts of such boxes together without the use of a twine binder.

15 Another object of the invention is to provide one of the locks with a handle whereby the box and its contents may be conveniently carried.

It will be understood that several of the 20 locks may be used to secure the several parts of the box together as may be deemed necessary, heavy parcels requiring four of the locks while light parcels may be securely packed with the use of only two locks.

25 An embodiment of the invention is shown in the drawing in which the same reference numeral is applied to the same portion throughout, but I am aware that there are many modifications thereof.

30 Figure 1 is an end elevation of the complete lock,

Fig. 2 is a side elevation therefor of the lock,

Fig. 3 is a perspective view of the lock 35 with a handle applied thereto,

Fig. 4 is a plan view of one of the registering slits of the two portions of the box,

Fig. 5 is a side elevation of a box with parts thereof broken away for purposes of 40 illustration and showing one of the locks with its handle in place on the box while three other locks are shown applied to the box,

Fig. 6 is a side elevation of a modified 45 form of the lock as it appears when cut out of a stiff piece of card board,

Fig. 7 is a side elevation of a lock such as is shown in Fig. 6 with the handle integral therewith,

50 Fig. 8 is an end view of a lock such as is shown in Fig. 1 with a double handle secured thereto, and

Fig. 9 is a side elevation of the lock shown in Fig. 8 and said handle.

55 In the drawing the numeral 1 indicates one portion of a telescoping suit box, 2 indi-

cating the other portion of said box which fits within the portion 1. Each of the edges of the box is provided with a long slot 3 having a U shaped slot 4 at the end thereof, 60 said slots being so positioned that when the box is assembled in position to carry the lead placed therein the said slots of both portions of the box will register. The two parts of the box are then secured together 65 by means of the lock 5, said lock comprising a flat top having two sharply V shaped portions 6 and 7 connected with each side edge. The V shaped portion may be connected at 8 with stitching or a staple as desired to the 70 bottom piece 9. The bottom piece 9 extends beyond the end of the top 5 as indicated at 10, the object being to provide a feeler for the lock, so that when it is inserted in place it will be pushed against the lip 11 and into 75 the long slot 3, the lock being pushed far enough so that the lip 11 can rise up into the plane of the material of the edge of the box as indicated in Fig. 5, thereby securing the lock firmly in place. 80

It will be understood that both of the edges of the box are inserted in the two V shaped portions of the lock. One of the locks has the handle 14 connected therewith, either by means of adhesive or staples as 85 may be desired, and extends far enough above the lock to provide a convenient hold. It will be understood that the ends of the handle 14 pass into the folded portion of the lock under the top 5. 90

Figs. 6 and 7 illustrate a form of the invention in which a flat piece of card board of suitable stiffness is used to form the lock or handle as may be desired. With this form of the invention the lock comprises an 95 elongated piece of material 15 having slots 16 and 17 cut in the ends thereof, one end having an elongated finger 18 to act as a feeler in putting the lock in place in the box. Such a number of the locks 15 as is desired may be provided while one for each box is provided with the integral handle 19. The locks connected with the handle 19 are made long enough so that they must be forced into position in the slot whereby they 100 will afford a support for the box. 105

A slightly modified form of handle is also shown in Figs. 8 and 9. In these figures L indicates a lock of substantially the same form as that shown in Figs. 1 to 5 inclusive, 110 to which lock is secured a double handle 21 and 22, the adjoining portion 23 of the han-

dle being connected to the lock by means of a suitable number of staples 24.

It will be understood that while it is contemplated that card board shall be used in the construction of the locks and handles herein any suitable material such as straw board, tin or any other material of that character may be made use of in the manufacture of the locks and handles.

10 The essence of the invention lies in the provision of a device which will distort the slot formed in the box as little as possible, and which will provide notches or recesses to receive the box edges thereby firmly securing the box in the locked position.

Having thus described my invention what I claim as new and desire to secure by Letters Patent of the United States, is as follows, modifications within the scope of the 20 claims being expressly reserved.

1. A box and lock therefor comprising a box body, a cover for the body telescopically fitting the body, the two parts of the box having registering slots, a lock for securing the two parts of the box together comprising a strip of material having two grooves and adapted to lie within the slots in the two parts of the box, the edges of the lock overlying the box within and without 30 the same, and a handle connected with the lock for supporting the box.

2. A box and lock therefor comprising a box body and a cover adapted to overlap the box body, said cover and box body having registering slots and a handle for supporting the box comprising a gripping portion and a terminal portion, having two grooves therein, which terminal portion is adapted to enter the registering slots and

overlap the box sides within and without 40 the box thereby locking the two parts together, said terminal portion also having an extension for entering the lock in the slots.

3. A box and lock therefor comprising a box body and a cover telescopically fitted 45 thereto, the sides of the cover and body having registering slots with movable tongues for closing one end of the slots, said tongues also permitting the insertion of a locking device which comprises a strip having two 50 grooves at the sides thereof, which strip is adapted to be inserted in the slots and to overlie the edges of the box adjacent the sides of the slots within and without the box.

4. A box and lock therefor comprising a box body and telescope cover therefor, the cover and body having registering slots shorter than the length of the box, and having movable tongues adjacent one end of the slots which tongues are wider than said slots and close one end thereof, a locking device formed of a strip of material with grooves at the sides thereof, and an entering tongue at one end thereof, which locking device is 65 adapted to be inserted in the slots to overlie the edges of the box and cover within and without the same, and a handle connected with the lock.

In testimony whereof I have hereunto set 70 my hand this 29th day of July, A. D. 1914, in the presence of the two subscribed witnesses.

CHARLES SCUDDER.
